(57) **CLAIM**

The ornamental design for a kitchen hood, as shown and described.

DESCRIPTION

FIG. 1 is a perspective view of the kitchen hood.

FIG. 2 is a front elevational view of the kitchen hood; and, FIG. 3 is a side elevational view of the kitchen hood with the opposite side being a mirror image of the same.

The top, bottom and back of the kitchen hood shown in FIGS. 1-3 form no part of the claimed design.
